UNITED STATES PATENT OFFICE

MERRITT D. ROBISON, OF SAN FRANCISCO, CALIFORNIA

DESIGN FOR A COMBINED CUTTLE BONE HOLDER AND TOY

Application filed February 21, 1933. Serial No. 47,280. Term of patent 14 years.

To all whom it may concern:

Be it known that I, MERRITT D. ROBISON, a citizen of the United States, residing at the city and county of San Francisco, State of California, have invented a new, original, and ornamental Design for a Combined Cuttle Bone Holder and Toy, of which the following is a specification, reference being had to the accompanying drawing, forming part thereof, in which

Fig. 1 is a perspective view from the front of a cuttle bone holder and toy.

Fig. 2 is a perspective view from the rear.

I claim:

The ornamental design for a combined cuttle bone holder and toy, substantially as shown.

MERRITT D. ROBISON.
